United States Patent Office.

JAMES H. MONCE, OF HOPKINSVILLE, OHIO.

Letters Patent No. 79,244, dated June 23, 1868.

IMPROVEMENT IN CHURN.

The Schedule referred to in these Letters Patent and making part of the same.

TO ALL WHOM IT MAY CONCERN:

Be it known that I, JAMES H. MONCE, of Hopkinsville, Warren county, and State of Ohio, have invented an Improvement in Churns; and I hereby declare the following to be an exact description thereof, reference being had to the accompanying drawings, and to the letters of reference marked thereon, making a part of this specification, in which—

Figure 1 represents a side elevation of the churn and its operating-devices.

Figure 2 represents a top view of the same.

The nature of my invention consists in the shape and construction of the pointed-toothed verge-wheel, with its connecting-verge and regulating-lever, having an upright pitman connected with the balance-wheel, that operates forward or backward, and in either direction, driving the upright lever of the churn.

A is a platform, upon which are erected upright frames, B B, that support the operating-devices of the churn. C is a coiled main-spring, that is wound up or operated by a key or lever, D.

A pinion, E, on the axle F of the spring C, drives the tooth-wheel G and moves the verge-wheel H, by means of which spring and gearing the verge J, with its adjustable and regulating-arm K, pitman L, and reversible balance-wheel M, with the lever N, of the churn P, are operated.

The horizontal lever R, operated by the regulating thumb-screw S, presses against the toothed wheel G, and regulates its speed.

The reversible balance-wheel M, with its pitman L and regulating-lever K, can also be used to operate any other machinery, as well as a churn, and I desire to apply the same devices for other purposes.

What I claim as my invention, and desire to secure by Letters Patent, is—

1. The arrangement and combination of the adjustable arm K, pitman L, and reversible balance-wheel M, as herein described and for the purposes set forth.

2. The combination of the pitman L and reversible wheel M, when constructed and operating as herein described, for the purposes set forth.
